MACHINE FOR GRINDING THE MAIN BEARING PINS AND CRANKPINS OF CRANKSHAFTS

Robert Musyl, Vienna, Austria

Application May 28, 1949, Serial No. 36,096
In Austria June 10, 1948

15 Claims. (Cl. 51—90)

1

This invention relates to a machine for grinding crankshafts, wherein both the main bearing pins as well as the crank pins can be ground during one single central clamping of the piece of work, it being possible to deal with a plurality of or all bearing points simultaneously by the provision of a plurality of grinding wheels.

The grinding of single crank pins, upon central location of the crankshaft, by the aid of a grinding wheel carrying out an oscillatory motion corresponding to the eccentric movement of the pin being ground has been proposed heretofore. However, in this case the oscillatory motion of the grinding wheel is derived in direct fashion from the crank pin being ground, which results in a number of disadvantages. The greatest drawback resides in the oscillatory and accordingly the irregular motion of the grinding wheel, which produce forces of inertia, which are incapable of being compensated and limit the rate and accuracy of the operation. A further disadvantage resides in the direct copying of the oscillatory motion of the grinding wheel from the crank pin being ground, whereby there occurs during the operation a considerable and above all, owing to the changing forces of inertia, variable deformation of the piece of work. A third disadvantage of the known apparatus consists in the fact that owing to derivation of the oscillatory motion of the tool in the copying process from the crank pin being ground an initially oval pin admittedly acquires a round form by corresponding arrangement of the copying device, but the position of its centre after completion of the grinding operation depends solely on the form of the pin prior to the initial treatment and cannot be varied by adjustment of the machine. Rectification of the centre of a pin which was incorrect prior to the grinding is accordingly impossible.

The known apparatus does, therefore, not satisfy the requirements of series production either as regards the circumferential velocity, and accordingly the output, or as regards accuracy, and is, therefore, employed solely as a machine for carrying out repair work.

A machine according to the invention for grinding the main bearing pins and crank pins of crankshafts comprises at least one grinding wheel, a support for said grinding wheel, means for rotating a crankshaft to be ground, during the grinding thereof, about the longitudinal axes of the main bearing pins of said crankshaft, and means for imparting to the axis of said grinding wheel a movement congruent to that of a crank

2

pin or main bearing pin to be ground when the respective crankshaft is mounted in the machine to rotate about the said longitudinal axes.

This machine therefore, completely avoids the disadvantages above referred to. The masses of the grinding device, rotating according to the invention in even fashion, can be wholly compensated without difficulty. The control movement is not derived from the piece of work, so that mutual interference between tool and piece of work cannot occur. Finally, owing to adjustability both of the phase position as well as the eccentricity of the centre of the grinding spindle without a break, any desired middle position of the crank pin to be ground can be obtained independently of its form and position prior to the grinding operation.

The arrangement according to the invention also results in a number of important advantages as compared with grinding machines having a stationary grinding-wheel centre point, which was the only grinding machine employed heretofore for the series production of crankshafts. Owing to the central location of the piece of work in the machine the device hitherto unavoidable for the purpose of positioning the work eccentrically is rendered unnecessary. For the same reason no strain is imposed on the piece of work by reason of centrifugal force, and accordingly a greater circumferential velocity can be employed. Further, the double-ended actuation of the piece of work heretofore necessary in the case of eccentric location in the machine in order to avoid deformation due to the driving movement may be dispensed with, whereby the design of the grinding machine is simplified and its total weight is reduced. The main advantage of the apparatus according to the invention is, however, the possibility of working on a plurality of or all bearing points of a crankshaft, whether main bearings or crank pins simultaneously in one operation.

If furthermore, as indicated in the following example, the machine is furnished with two bed plates disposed on the same level and movable selectively into the operative position, it is possible during the grinding of a piece of work the check up in the clamping position on a second piece of work already finished, which can then be exchanged for a piece of work to be treated, whereby a considerable reduction in the intermediate periods is achieved. In this way it is possible by using, for example, a machine having four grinding wheels, to reduce the time required for working on the crank pins of a crankshaft

having four throws to less than one quarter as compared with the known machines.

In order that the invention may be more readily understood, preferred embodiments thereof will now be described, by way of example, with reference to the accompanying drawings, in which

Fig. 1 illustrates the principle of operation of a machine according to the invention.

Fig. 2 is a diagram of control in respect of 10 the movement of the grinding wheels.

Figs. 3 and 4 illustrate in side view and partial longitudinal section respectively a modified embodiment of the drive and the mounting of the grinding wheel.

Figs. 5 and 6 show in longitudinal section and side view respectively the method of compensating the eccentrically rotating weight of the grinding wheel.

Figs. 7 and 8 and 9 show in front elevation, 20 plan and side elevation respectively a grinding machine of the single-spindle type, and

Figs. 10, 11 and 12 are similar views, showing a four-spindle arrangement for grinding the crank pins of a four-throw crankshaft.

According to Fig. 1, the crankshaft to be ground is rotated at even circumferential velocity about its central axis 1 in the direction of the arrow. The crank webs are designated 2, whilst the crank pin to be worked upon by the grinding wheel 4 is designated 3. In addition to the extreme front position of the crank pin 3 and the grinding wheel 4 shown in full lines there are shown in dotted lines two further positions which are reached upon rotation of the piece of work by 120° and 240° respectively.

The grinding wheel spindle 5 is driven by way of a belt by a motor not shown in Fig. 1. It is eccentrically mounted, with an eccentricity e_1 , in an eccentric sleeve 6, which in turn is mounted, with an eccentricity e_2 in the drum 7, which is rotatably mounted in the grinding wheel support. The total eccentricity e of the grinding wheel spindle is accordingly the geometric total of the part-eccentricities e_1 and e_2 . If these are made to be exactly the same ($e_1=e_2$), the total eccentricity e can be varied without a break from $e_1-e_2=0$ to $e_1+e_2=2e_1$ by rotation of the eccentric sleeve 6 in the drum 7. The total eccentricity is so adjusted in a manner to be described later that it is equal to the eccentricity of the crank pin to be ground. The drum 7 runs synchronously and in equal phase with the crank pin to be ground, which is accordingly acted upon with the adjusted eccentricity and phase position. The diameter of the treatment is determined by adjusting the grinding wheel support in a line connecting the centre of the drum 7 with that of the workpiece 1.

Fig. 2 shows the drive for the control movement of the grinding wheel. The references 1 to 7 and also e_1 , e_2 and e correspond to Fig. 1. Fig. 2 furthermore shows the motor, mounted in the grinding wheel support, for the control movement, which motor is coupled electrically or mechanically with the exactly synchronously running drive for the piece of work. It drives the drum 7, rotatably mounted in the support 13, by way of a pinion 9 and spur wheel 10. The same figure shows the arrangement for unbroken adjustment of the eccentricity of the grinding spindle. This adjustment takes place by relative rotation of the eccentric sleeve 6 and the drum 7, which during the grinding operation are locked in relation to one another. In order

to ensure that this adjustment will take place without variation of the phase position of the resulting eccentricity e , the eccentric sleeve 6 and the drum 7 are coupled together by a planet-wheel gear 16, 17, 18 and 19. If the wheel 16 of the planet gear having the inner teeth is blocked by means of the locking pin 12 and the externally disposed latching device, i. e. the latching teeth 11, in the grinding wheel support 13, and the drum 7, the control drive 8 being disengaged and the locking between the eccentric sleeve 6 and the drum 7 disconnected, is rotated by way of the hand wheel 14 and the pinion 15, the gear wheel 17 will move over the stationary inner teeth 16 and cause by way of the intermediate wheel 18 and the teeth 19 a rotation of the eccentric sleeve 6 in the opposite direction and by twice the angle. Since, as already set forth, the eccentricities e_1 and e_2 are equal, the direction of the resulting eccentricity remains on the basis of adherence to geometric laws unchanged.

When the desired eccentricity has been adjusted, the blocking device, not shown, between the eccentric sleeve 6 and the drum 7 is made to engage, and the locking pin 12 is released. By actuating of the hand wheel 14 whilst the control drive 8 and 9 is still disconnected the drum 7 can now be rotated in relation to the piece of work, whilst the eccentricity remains the same, 25 and the phase position adjusted. When this adjustment has also been made the hand drive 14 and 15 is disconnected by means of a clutch, which operates without play, and the control motor drive 8 and 9 is connected, the apparatus 30 then being ready for operation. Synchronous operation of the work and of the drum 7 may be effected mechanically by the provision of a bevel gear wheel 50 on the main drive shaft 51 for the grinding wheel 4. Gear wheel 50 meshes 40 with a bevel gear wheel 52 at the end of a splined shaft 53. The latter extends axially slidably into a corresponding female end portion of a shaft 54 on whose far end a bevel gear wheel 55 is fixed. The latter meshes with a bevel gear wheel 56 on the drive shaft for the work, i. e. the crank shaft 1, 2, 3. The transmission ratio 45 between wheel 50 and wheel 56 is 1:1. The telescope connection between shafts 53 and 54 permits the use of the device for working crankshafts of different shaft diameters. The grinding wheel support 13 is displaceable from and toward the work piece in the conventional manner. Mechanism 50 to 56 is shown in dotted lines in Fig. 2 because the mechanism may be disposed in a plane in front or in the rear of the 50 plane of Fig. 2.

Fig. 3 is a longitudinal section through the grinding wheel spindle mounting, showing the grinding wheel spindle 5, the eccentric sleeve 6 and the drum 7, together with the bearings 20 and 21 therefor in the grinding wheel support 13 (Fig. 2). There are also shown in Fig. 3 the driving belt pulley 26 for the grinding wheel 4, and the driving belt 24.

Fig. 4 is a side elevation of the grinding wheel drive, the references 1 to 7 agreeing with the preceding figures. The driving motor 22 is firmly mounted on the grinding wheel support 13 (Fig. 2), and accordingly does not participate in the 60 control movement of the grinding wheel 4. The power transmission from the stationary motor to the grinding wheel spindle 5 rotating synchronously with the crank pins 3 to be ground takes place by way of two belt drives 23 and 24. 70 The driving belt pulley 25 is mounted on the mo- 75

tor shaft, and the driven belt pulley 26 on the grinding wheel spindle 5. The intermediate pulley 27 receiving the two belts 23 and 24 is guided by means of two oscillatory arms 28 and 29, which are pivotally mounted on the shaft of the motor 22 and the grinding wheel spindle 5 respectively. There is thus obtained a length of the two belt drives which is independent of the control movement of the grinding wheel spindle 5.

The mounting for the grinding wheel spindle is so designed that, with the exception of the grinding wheel, the eccentrically rotating masses are fully compensated independently of the extent of adjusted eccentricity.

The compensation of the weight of the eccentrically rotating grinding wheel, which varies in accordance with diameter and width thereof, takes place by means of the device illustrated in Figs. 5 and 6. The references 4 to 7 and also 21 and 22 correspond to the preceding figures. On the grinding wheel spindle 5 there is rotatably mounted a rocker 30, the upper end of which is pivoted to the double lever 31. The second arm of the double lever 31 mounted on the support 13 (Fig. 2) is so constructed that its effective lever length, i. e. the distance of the adjustable nut 32 from the centre of the lever can be varied by rotating the spindle 33 by way of bevel wheels 34 and 35 and the hand wheel 36. The adjustable nut is acted upon by the compression spring 37, which bears with its other end against the grinding wheel support 13 (Fig. 2), and the tension of which is so calculated that equilibrium is maintained with the weight of the grinding wheel 4 suspended on the rocker 30. Adaptation to the variable weight of the grinding wheel 4 is effected by varying the effective lever arm of the compression spring by the aid of the hand wheel 36, in which connection the adjusted weight can be ascertained from a scale, not shown, connected with the hand wheel.

In Figs. 7, 8 and 9 there is shown a machine in elevation, plan and side elevation respectively, which is furnished with the arrangement according to the invention. On the machine bed 38 there is mounted in longitudinally shiftable fashion the bed plate 39 with the spindle head stock 40 and the tail stock 41. By means of a hand wheel 42 and a second hand wheel 43 there can be performed a longitudinal displacement of the workpiece 44 clamped between the tail stock and the spindle stock and also an adjustment of the grinding wheel 4. The grinding wheel 4 is mounted on the grinding wheel support 13, which is stationary, whilst the grinding wheel 4 moves as stated above. The grinding wheel support 13 is mounted on a wedge-shaped lower portion 45, so that the adjustment occurs obliquely downwards in order to keep the points of the spindle stock and tail stock as low as possible, and accordingly to make the machine as stable as possible.

In Figs. 10, 11 and 12 there is shown in elevation, plan and side elevation respectively, as example of a multiple crankshaft grinding machine for the large-scale production of crankshafts, an apparatus for handling four bearing points in one operation. There are provided in each case to the front and rear of the machine bed two supports 13, 13a, 13b and 13c, there again being employed the oblique path of approach in order to keep the height of the points of the spindle stock and tail stock as low as possible, and to make the width of the bed plate as small as possible. The single grinding units are arranged to be

adjustable independently of one another, both as regards the total eccentricity e to be adapted to the radius of the crankshaft as well as with regard to the phase position.

5. In Figs. 10, 11 and 12 two bed plates are arranged side by side, so that there is room for two spindle stocks 40 and 40a and two tail stocks 41 and 41a and also two pieces of work 44 and 44a. It is accordingly possible during the treatment of one crankshaft to examine the second, already ground crankshaft in the position in which it is ground, and to exchange the same for a fresh piece of work, without loss of time. When the grinding operation on the crankshaft being dealt with is completed, the next shaft, which has been set up in the meantime, is moved into the operative position by simple longitudinal displacement of the bed plate.

What I claim is:

20. 1. An external grinding machine particularly for crankshafts comprising, in combination, a plurality of individual grinding units, each unit comprising an eccentric gear, a grinding wheel rotatably and eccentrically supported by said gear, drive means for said gear, and means to rotate said grinding wheel.

25. 2. A grinding machine as defined in claim 1, each grinding unit comprising adjusting means connected with said gear for adjusting the eccentricity at which the grinding wheel is supported.

30. 3. A grinding machine comprising, in combination, an eccentric gear unit comprising a first member rotatably and eccentrically supporting a grinding wheel, a second member eccentrically supporting said first member, a rotatable mounting for a work piece, means to rotate said mounting, means synchronized with said last mentioned means to rotate said second member, means to rotate said grinding wheel, means independent of said second mentioned means for independently rotating said second member, and a planetary gear interposed between said two members for rotating said first member upon rotation of said 45 second member by said independent means, through the same angle of rotation as said second member.

40. 4. A grinding machine comprising, in combination, an eccentric gear unit comprising a first member rotatably and eccentrically supporting a grinding wheel, a second member eccentrically supporting said first member, a rotatable mounting for a work piece, means to rotate said mounting, means synchronized with said last mentioned means to rotate said second member, means to rotate said grinding wheel, and means independent of said second mentioned means for independently rotating said second member and simultaneously rotating said first member relatively to said second member through the same angle of rotation as said second member is rotated, said last mentioned means comprising lock means locking both members against relative rotation.

45. 5. A grinding machine comprising, in combination, an eccentric gear unit, a grinding wheel shaft rotatably and eccentrically supported by said unit, a rotatable mounting for a work piece, means to rotate said grinding wheel shaft, suspension means connected with said shaft and comprising means for varying the suspensive effect for compensating the gravity effect of the rotating masses while said shaft is moved parallel to itself by said unit.

75. 6. A grinding machine comprising, in combina-

tion, an eccentric gear unit, a grinding wheel shaft rotatably and eccentrically supported by said unit, a rotatable mounting for a work piece, means to rotate said grinding wheel shaft, variable effect suspension means connected with said shaft and comprising resilient means for varying the suspensive effect of said suspension means for compensating the gravity effect of the rotating masses while said shaft is moved parallel to itself by said unit.

7. A grinding machine as defined in claim 6, comprising adjusting means connected with said suspension means for adjusting the tension of said resilient means.

8. A grinding machine comprising, in combination, an eccentric gear unit, a grinding wheel shaft rotatably and eccentrically supported by said unit, a rotatable mounting for a work piece, means to rotate said grinding wheel shaft, suspension means connected with said shaft and comprising means for varying the suspensive effect for compensating the gravity effect of the rotating masses while said shaft is moved parallel to itself by said unit, said suspension means comprising a rocker member having one end rotatably connected with said shaft, a bell crank lever means swingable on a stationary fulcrum and having one arm movably connected with the other end of said member, and a spring having a fixed end and an end connected with the other arm of said lever means.

9. A grinding machine as defined in claim 8, the point of connection of said spring with the other arm of said lever means being adjustably movable towards and from the fulcrum of said lever means for adjusting the effect of said spring on said suspension means.

10. A grinding machine comprising, in combination, an eccentric gear unit, a grinding wheel rotatably and eccentrically supported by said unit, a rotatable mounting for a work piece, drive means to rotate the said mounting, drive means to rotate said unit, disconnectable synchronizing means affording synchronized operation of both drive means and temporary suspension of such operation, and means independent of said drive means to rotate said grinding wheel.

11. A grinding machine comprising, in combination, an eccentric gear unit, a grinding wheel shaft rotatably and eccentrically supported by said unit, a rotatable mounting for a work piece, means to rotate the said mounting, means synchronized with said last mentioned means to rotate said unit, drive means to rotate said grinding wheel shaft, said drive means comprising a shaft rotating on a stationary axis, a link member swingably supported by said grinding wheel shaft, an arm member swingable on said shaft which rotates on a stationary axis, a pin swingably interconnecting said link member and said arm member, a pulley on said pin, flexible means drivingly connecting said shaft rotating on a stationary axis and said pulley, and a second flexible means drivingly connecting said pulley with said grinding wheel shaft.

12. A grinding machine comprising, in combination, a plurality of individual grinding units, each unit having an eccentric gear having horizontal rotation axes, a grinding wheel rotatably and eccentrically supported by said eccentric gear, and means to rotate said grinding wheel; a mounting for a work piece rotating on a horizontal axis, means to rotate said mounting, means synchronized with said last mentioned means to rotate said eccentric gears; and a machine bed supporting said units in a row.

13. A grinding machine comprising, in combination, a plurality of individual grinding units, each unit having an eccentric gear having horizontal rotation axes, a grinding wheel rotatably and eccentrically supported by said eccentric gear, and means to rotate said grinding wheel; a mounting for a work piece rotating on a horizontal axis, means to rotate said mounting, means synchronized with said last mentioned means to rotate said eccentric gears; and a machine bed supporting a number of said units on one side and the other units on the other side of the rotation axis of said rotatable mounting.

14. An external grinding machine particularly for crankshafts comprising, in combination, a plurality of individual grinding units, each unit comprising an eccentric gear, a grinding wheel rotatably and eccentrically supported by said gear, drive means for said gear, and means to rotate said grinding wheel; a plurality of mountings for work pieces rotating on a horizontal axis, means synchronized with said drive means to rotate said mountings, and a machine bed coaxially supporting said mountings.

15. An external grinding machine particularly for crankshafts comprising, in combination, a plurality of individual grinding units, each unit comprising an eccentric gear, a grinding wheel rotatably and eccentrically supported by said gear, drive means for said gear, and means to rotate said grinding wheel; a plurality of mountings for work pieces rotating on a horizontal axis, means synchronized with said drive means to rotate said mountings, and a machine bed coaxially and axially displaceably supporting said mountings.
